UNITED STATES PATENT OFFICE.

JOHN L. SHRODE, OF ST. LOUIS, MISSOURI.

AUTOMATIC CONTROL VALVE FOR REFRIGERATING SYSTEMS.

Application filed March 14, 1927. Serial No. 175,248.

The object of this invention is to provide a simple, compact and efficient device whereby a substantially constant ratio between the temperature of the refrigerant and product 5 to be refrigerated will be automatically maintained. The invention is illustrated in the accompanying drawings and will be hereinafter fully set forth.

In the drawings:

- 10 Figure 1 is a diagrammatic elevation of a refrigerating system in which the invention is embodied.
- 15 Figure 2 is an enlarged vertical section through the reducing valve and thermal control chamber.
- Figure 3 is a section on the line 3—3 of Figure 2.
- Figure 4 is a section on the line 4—4 of Figure 3.
- 20 Referring to Figure 1, the reference numeral 1 denotes a compressor or pump which may be of any approved form, and 2 designates the condensing coils through which the refrigerant is caused to circulate from the 25 pump under pressure to be stored in the receiver 3. A pipe 4 connects the receiver 3 with the inlet side of a pressure-regulating valve 5 and the cooling coil 6 is connected with the outlet side of the said valve. A casing 7 above the pressure-regulating valve is 30 connected on one side with one end of the cooling coil 6 and on its other side is connected through a return pipe 8 with the compressor or pump 1.
- 35 The pressure-regulating valve, which is indicated as an entirety by the numeral 5 in Figure 1, comprises a block or casting 9 having an inlet port 10 in one side connected to the pipe 4, and at its opposite side having a 40 discharge tube 11 which projects into the cooling coil 6. In the under side of the block or casting 9 is a central chamber 12 connected through a passage 13 with the inner end of the inlet port 10, and this chamber 12 is 45 closed by a cap or plug 14 having a central socket or chamber 15 therein to accommodate a plunger 16 and a spring 17 disposed between the bottom of the socket and the under side of the plunger. A central passage 18 50 rises through the block 9 and a branch passage 19 extends from said passage 18 to establish communication between the same and the discharge tube 11. At the upper end of the passage 18 is a packing box 20 whereby packing 55 21 will be held closely about the stem 22 and leakage of the refrigerant around the said stem will be avoided. This stem 22 has its lower end resting on the reduced upper end 23 of the valve pin 24 and acts as a medium through which pressure is applied to the valve 24 to open the valve and permit the refrigerant to flow through the passage 18 and out through the passage 19 into the cooling coils 6. It is evident that the spring 17 tends constantly to seat the 60 valve and a greater pressure exerted through the stem 22 will force the valve 24 away from its seat, permitting the refrigerant to flow through the several passages into the cooling coil 6. The top or upper side of the block 70 or casting 9 is centrally recessed, as shown at 25, and an opening 26 is formed through the block to establish communication between the said recess 25 and the chamber or enlargement 27 surrounding the tube 11, and in communication with the cooling coil which has a flange connection bolted to the valve body or casting 9, as will be understood. A flexible diaphragm 28 extends across the recess or chamber 25 and the upper extremity of the 75 stem 22 bears against the under side of said diaphragm, the diaphragm being secured by bolts 29 inserted through the flange 30 of an upper casting 31 and through the marginal portion of the diaphragm into the top of the 80 casting 9, as shown clearly in Figure 2. The casting 31 constitutes the body of the casing 7 and has a central bore or chamber 32 which is enlarged in its lower portion to define a chamber 33 alined with the passage 18 in the valve 85 block 9 and housing an expansion spring 34. The said spring 34 bears at its lower end upon a plate 35 which has its under surface convex and resting directly upon the diaphragm, the point of contact being directly opposed to the 90 upper end of the stem 22. The upper end of the spring 34 bears against a plate 36, the upward movement of which is limited by contact with the shoulder 37 formed at the upper end of the chamber 33 and the lower end 95 of the bore 32. Threaded through the top of the casting 31 is an adjusting rod 38 which has its upper end suitably formed to be engaged by a turning tool and its lower end resting upon the presser plate or cap plate 36, 100 a packing box 39 being mounted on the top of the casting 31 around the adjusting rod to prevent leakage. By screwing down on the stem 38 the tension of the spring 34 may be 105 regulated and pressure exerted to overcome the spring 17 and open the valve 24. Concentric with the bore 32 a circular chamber or 110

passage 40 is formed in the casting 31 and a small port 41 is formed through the inner wall of this chamber to establish communication between the same and the bore 32. A valve 42 is mounted in the outer wall of the circular chamber in axial alignment with the port 41 to admit gas from the annular chamber 40 into the thermal chamber 32, 33. At right angles to the said valve 42 openings 43 are formed in the casting to receive the ends of the coil 6 and the pipe 8, as will be understood. Cap plates 44 may be secured to the opposite sides of the casting 31 around the ends of the coil 6 and the pipe 8 respectively to hold packing to the said element and thereby prevent leakage of the circulating refrigerant. To facilitate the application of these caps or packing plates, threaded sockets 45 are provided in the sides of the casting 31, as shown most clearly in Figure 4.

The operation of the apparatus will, it is thought, be readily understood. The refrigerating medium in liquid form under high pressure passes from the receiver 3 through the pipe 4 to the inlet passage 10 of the pressure-regulating valve and thence flows through the passage 13 to the chamber 12 to rise through the passage 18 and pass out through the port 19 into the cooling coil. The diaphragm 28 is subjected to the pressure of the gas in the cooling coil through the opening 26 and is also subjected to the pressure of the spring 17 exerted through the follower or plunger 16 and the valve 24. The adjusting rod 38 is rotated so that the tension of the spring 34 will just balance the pressure exerted on the underside of the diaphragm 28 and, consequently, the valve 24 will be in open position so that circulation of the refrigerant may occur. The refrigerant flowing through the coil 6 will absorb heat from the surrounding air and, consequently, will be raised in temperature and will be capable of exerting a greater pressure than when it entered the cooling coil. The heating of the refrigerant within the cooling coil and the retraction of heat from the surrounding air causes a deposit of frost upon the coil and this frost ordinarily reaches back to the pressure-regulating valve. It is here to be noted that the diameter of the end 11 of the cooling coil is not greater than the diameter of the inlet passage in the valve block 9 so that the refrigerant cannot expand within the valve and the expansion will not occur until the refrigerant has passed some distance from the valve so that there will be no deposit of frost upon the valve to interfere with its successful operation in my apparatus. When a predetermined pressure is obtained in the coil 6 and circular chamber 40, the valve 42 is opened to establish the same pressure in the thermal chamber 32. The valve 42 is then closed trapping a volume of gas in the chamber 32 of the same pressure as that in the coil

6 and the chamber 40. This pressure is naturally attained in the spring chamber 33 and is also transmitted to the top of the diaphragm 28. As the amount of pressure allowed in this chamber is somewhat less per square inch than the pressure of the spring 17, the valve will remain closed until an additional pressure is applied by screwing down on the adjusting stem 38. As the pressure of the gas in the thermal chamber 32 and 33 is in direct relation to its temperature, it will be readily seen that any increase or decrease in temperature of the gas in the chambers 32 and 33 will cause the valve to open or close respectively. The desired suction pressure at which the machine is to operate is provided by the adjusting stem 38 and a balanced condition between the springs 17 and 34 is set up, and any increase in pressure above or below the diaphragm 28 will cause the valve to open or close respectively. In other words, the opening and closing of the valve will be automatically governed by either an increase or decrease in pressure in the coil 6 and an increase or decrease in pressure of the gas in the chamber 32. It is readily seen that as the machine operates, the coil 6 will become gradually cooled and as that part of the pipe that is connected to the block 31 becomes cooled, the cooling effect on the gas trapped in the chamber 32, will cause a decrease in pressure which will cause the valve 24 to close slightly. As the temperature of the refrigerant is in direct relation to its pressure, the slight closing of the valve will permit less refrigerant to flow, but at a lower temperature, through the coil 6. This lowering of temperature of the refrigerant will further cool the inert gas in the chambers 32 and 33 thereby further decreasing the pressure, which in turn will cause the valve to close still more. This closing of the valve is continually going on until the room that is being refrigerated is brought to the desired temperature, at which point the machine will be caused to stop by the action of a thermostat in the room. When the machine stops, refrigerant will continue to flow into the coil 6 increasing the pressure therein. This pressure will be transmitted through the passage 27 and through the orifice 26 into the recess 25 and exert its pressure on the diaphragm 28 causing the valve to close and remain closed until the machine again starts.

Having thus described the invention, I claim:

1. In a refrigerating system, the combination of a pressure regulator including a valve block having an inlet and an outlet, a diaphragm over the block, a passage lateral to the outlet leading from the cooling coil of the system to the diaphragm for subjecting one side of said diaphragm to the pressure in the cooling coil, the outlet from the valve block extending into the coil at a point re-

5
mote from the block, a valve bearing against
said side of the diaphragm and arranged to
control the flow of refrigerant through the
inlet and outlet, a thermal chamber disposed
above the diaphragm, said thermal chamber
including a valved by-pass to establish com-
munication with the return line of the refrig-
erating system, a pressure plate within the
thermal chamber receiving pressure through
10 the by-pass and bearing on the diaphragm in
opposition to the valve, and means for regu-
lating the normal pressure of said plate.

2. In a refrigerating system, the combina-
15 tion of a valve block having a central recess
in its upper side and having inlet and outlet
passages and an enlarged bore around the
outlet passage and an opening extending be-
tween said bore and said recess, a discharge
20 tube leading from the inner part of the out-
let passage through the enlarged bore of said
passage into the cooling coil, a diaphragm se-
cured upon the block and extending over said
recess, a valve yieldably mounted in the valve
25 block between the inlet and outlet passages
and exerting pressure against the diaphragm,
a block secured upon the valve block over the
recess in the top thereof, a thermal chamber
within the last-mentioned block, a return line
passage through the block, a pressure plate

30 mounted in the thermal chamber and bearing
yieldably upon the diaphragm in opposition
to the valve, and a port above the pressure
plate establishing communication between
the return line passage and the thermal
35 chamber.

3. A valve structure for the purpose set
forth comprising a body having inlet and out-
let passages, a diaphragm over said body, a
valve between the inlet and outlet passages,
means tending to raise the diaphragm for
40 seating the valve, a body secured on the valve
body over the diaphragm and having a ther-
mal chamber open to the diaphragm and hav-
ing an annular chamber around the thermal
chamber, said thermal chamber having a stop
45 shoulder intermediate its height, a pressure
plate within the chamber below said shoulder,
an expansion spring between said plate and
the diaphragm, an adjusting screw mounted
in the top of the last-mentioned body and
50 bearing on the pressure plate whereby pres-
sure may be exerted on the diaphragm in oppo-
sition to the means tending to raise the same,
a port in the wall of the thermal chamber,
and a valve mounted in the wall of the circu-
55 lar chamber to close said port.

In testimony whereof I affix my signature.
